1 Sheet Drawing, 6 Pages Specification

A drawing board is provided with a workface, an underface and a tray for holding drawing utensils or the like. The tray is arranged with respect to the workface so that a sheet of drawing paper supported on such workface, when overlapping an edge of the drawing board, will be partially disposed in such tray. A slot in the tray is of dimensions suitable for passage therethrough of the supported drawing sheet and communicates with a chamber located on the underface of the drawing board. Accordingly, a draftsman may remain seated at the drawing board and work on all areas of the supported sheet by feeding such sheet through the tray slot and into and out of the chamber.
